UNITED STATES PATENT OFFICE.

LEWIS GRAFFLIN, OF OCEAN VIEW, VIRGINIA, ASSIGNOR, BY DIRECT AND MESNE ASSIGNMENTS, TO TWO-SEASON PROCESS, INCORPORATED, OF NORFOLK, VIRGINIA, A CORPORATION OF VIRGINIA.

HEATING SYSTEM.

Application filed January 17, 1927. Serial No. 161,611.

My invention relates to hot air heating systems for buildings, such as dwellings, while not necessarily restricted to this use.

An important object of the invention is to provide a heating system of the above mentioned character, which will supply the maximum amount of heated air to the desired point or points, with the minimum amount of fuel.

10 A further object of the invention is to provide a system of the above mentioned character which is cheap to manufacture and has a low upkeep, in use and operation.

15 A further object of the invention is to provide means whereby the heat exchange between the source of heat and the air is effected through the medium of a mass of water whereby the desired temperature may be more readily maintained.

20 Other objects and advantages of the invention will be apparent during the course of the following description.

In the accompanying drawings, forming a part of this specification, and in which 25 like numerals are employed to designate like parts throughout the same,

Figure 1 is a central vertical longitudinal section through a heat unit embodying my invention parts in elevation, and,

30 Figure 2 is a horizontal section taken on line 2—2 of Figure 1.

In the drawings, wherein for the purpose of illustration, is shown a preferred embodiment of my invention, the numeral 5 designates an air pressure holding tank or shell, which is preferably circular in cross section. This tank is closed at its top and bottom, as shown. The tank or shell 5 is arranged within an outer water holding casing or 35 jacket 6, preferably circular in cross section, having a closed bottom 7, while its top is open or otherwise in free communication with the atmosphere. The outer jacket has a substantially greater diameter than the tank 5 providing a space 8, extending about the sides and bottom of the tank 5, and this space is filled with water, up to a desired level, as will be described. The tank 5 is held upon spaced supports or angle irons 9, 40 and the top of the tank preferably extends above the top of the outer casing or jacket 6, for a slight distance. The outer casing or jacket is in turn supported upon a bed 10, constituting a fire box, and a heating ele-

ment 11 is arranged within this fire box, beneath the bottom of the casing 6, as shown. I preferably employ a blue flame kerosene vapor oil stove burner, although the heating element may be in other forms, such as a gas burner, or any electrical heating unit.

Water is supplied in the bottom or lower end of the casing or jacket 6 through a pipe 12, which may be equipped with a suitable valve 13. This pipe may lead to a water main or any other suitable source of water. Connected with the upper end of the casing or jacket 6 is an overflow pipe 14, which determines the elevation of the water in the casing or jacket 6 and which may discharge to a sewer or to any other suitable point.

70 The numeral 15 designates an air compressor or pump, shown in the form of a rotary blower, while any other type of pump or compressor may be employed, such as a reciprocating pump or the like. The intake side of this compressor is connected with a pipe 16, leading to the exterior of the building to draw in fresh air. The outlet side of the compressor is connected with a pipe 17 passing through the casing or jacket 6, but having no communication therewith and leading into the bottom of the inner tank or shell 5, as shown.

75 Connected with the pipe 17 is a riser 18, preferably extending beyond the roof of the house, or to some other suitable exterior point, and this riser is equipped with a safety blower valve 19, which may be adjusted to permit of the escape of air pressure at any desired pressure, such as when the pressure exceeds two or two and one-half pounds per square inch. By locating the safety valve exteriorly of the building, the hissing noise will not be heard.

80 Hot air take-off pipes 22 lead into the top of the tank or shell 5 and are equipped with preferably two-way valves 23, of any well known or preferred type. Each pipe may lead to any desired point of heat distribution and one pipe is shown as connected with a register 24, arranged in the floor of the room above the heating unit. It will, of course, be understood that any number of pipes 22 may be employed and these may lead to any desired points of heat distribution.

85 Arranged within the tank or shell 5 are horizontal alternately disposed baffle plates

26 and 27, the outer ends of which are secured to the walls of the inner tank or shell 5 and form a gas-tight joint therewith, while their inner ends are spaced from the opposite side of the tank or shell 5. The baffles, therefore, overlap and produce a tortuous passage for the travel of the air, retarding its movement and effecting a better heat transfer.

10 In use, I prefer to maintain an air pressure within the tank or shell 5 between one and one-half to three pounds per square inch, and the safety valve 19 may be adjusted to prevent the increase of pressure above these limits. However, the invention is in no sense restricted to these precise pressures. When the take-off pipes 22 are suitably partly or entirely open, the heated air passes to the points of distribution, and the compressor or rotary blower is driven at a suitable speed to maintain the pressure substantially constant in the tank 5 while the heated air is escaping from the pipes. The pump 5 is preferably driven by an electric motor, although any source of power may be employed. When the burner 11 is operated the heat from the same is transmitted to the jacket 6 and water therein, and the water effects a heat exchange with the compressed air in the tank 5. It is preferred that the water within the jacket 6 be maintained at a temperature of about boiling point or slightly beneath the same, that is, slightly below 212° F. The steam or vapor from the water jacket does not in any way enter the distribution pipes 22, but will pass to the atmosphere exteriorly of the tank 5. Instead of filling the casing or jacket 6 with water, any other suitable liquid may be employed, having a relatively low boiling point.

It is to be understood that the form of my invention, herewith shown and described, is to be taken as a preferred example of the same and that various changes in the shape, size and arrangement of parts may be resorted to without departing from the spirit of my invention or the scope of the subjoined claims.

Having thus described my invention, I claim:—

1. In a hot air heating system, an air pressure storage tank, a water jacket surrounding the storage tank, means for applying heat to the exterior of the water jacket, means to withdraw heated air from the air pressure storage tank, and means for supplying air under pressure to the tank and

maintaining the pressure substantially constant during the discharge of the air through the withdrawing means.

2. In a hot air heating system, an air pressure storage tank, a water jacket surrounding the storage tank and in communication with the atmosphere and free from communication with the interior of the storage tank, means for applying heat to the exterior of the water jacket, means to withdraw heated air from the air pressure storage tank, and means for supplying air under pressure above atmospheric pressure to the interior of the storage tank.

3. In a hot air heating system, an air pressure storage tank, a plurality of baffles arranged therein in spaced overlapping relation to provide a tortuous passage for the travel of the air, a water jacket surrounding the tank and having communication with the atmosphere and free from communication with the interior of said tank, means for supplying air under pressure in excess of atmospheric pressure to one end of the tank, and means for withdrawing the heated air from the opposite end of the tank.

4. In a hot air heating system, a substantially vertical air pressure storage tank, a plurality of generally horizontal baffles arranged therein in spaced overlapping relation to provide a tortuous passage for the travel of the air, a substantially vertical water jacket surrounding the storage tank and having its top in free communication with the atmosphere and being free from communication with the interior of said tank, means for applying heat to the bottom of the water jacket, means for supplying air under pressure in excess of atmospheric pressure to the bottom of said tank, and means for withdrawing heated air from the top of the tank.

5. In a hot air heating system, a substantially vertical water jacket having its bottom closed and its top open, a substantially vertical air pressure storage tank arranged within the jacket and having its side and bottom spaced from the side and bottom of said jacket, a heating element arranged beneath the bottom of the jacket, an air compressor supplying compressed air to the bottom of said tank, outlet means for the heated air connected with the top of the tank, and spaced baffles arranged within the tank between the air inlet and outlet.

In testimony whereof I affix my signature.
LEWIS GRAFFLIN.
